UNITED STATES PATENT OFFICE.

CHARLES CLARK AND JOSEPH MANNING, OF SAN FRANCISCO, CALIFORNIA.

FREIGHT-CAR.

1,229,714.

Specification of Letters Patent. Patented June 12, 1917.

Application filed October 11, 1916. Serial No. 124,985.

To all whom it may concern:

Be it known that we, CHARLES CLARK and JOSEPH MANNING, citizens of the United States, residing at the city and county of San Francisco and State of California, have invented certain new and useful Improvements in Freight-Cars, of which the following is a specification.

The present invention relates to freight cars particularly adapted for the transportation of automobiles.

Under the present methods for shipping vehicles, and especially automobiles, in railway freight cars, either the vehicles are partially dismantled, by the removal therefrom of the wheels, fenders and other exterior parts, and each part crated; or the vehicles are placed within the cars in a practically complete condition, and securely and firmly fastened by means of blocks and braces to prevent any movement thereof within the car during transit.

In either case the amount of material and labor necessary for packing the vehicles within the car constitutes a very considerable item of expense. For example, the lumber required for building the crates or for making blocks, braces and scaffolding for one carload of automobiles frequently amounts to one ton in weight. This material is thrown away when the car reaches its destination, and therefore results in a dead loss. Moreover, transportation charges must be paid on said material at the same rate as the rate for the automobiles. In addition to this, a considerable amount of labor is required for constructing the crates or braces and for unloading the automobiles at their destination.

The method of blocking and bracing the vehicles within the car is, moreover, destructive to the car itself, for the reason that the blocks and braces are nailed to the car body, thereby mutilating it, and by just so much shortening its life. Any attempt to load the vehicles in a manner involving less expense than that heretofore described, involves the danger of damage to the vehicles in transit, by being torn loose from their fastenings and thrown about within the car.

The object of the present invention is to

provide a railway freight car into which vehicles may be loaded easily and rapidly, and within which they may be firmly secured to prevent damage in transit, and from which they may be unloaded with equal ease. For this purpose the car is provided with appliances particularly adapted for the attainment of the desired objects, but so constructed as to not interfere in any manner with the use of the car in the ordinary manner for other forms of freight.

In order to comprehend the invention, reference should be had to the accompanying sheets of drawings, wherein—

Figure 1 is a transverse sectional elevation of the freight car embodying our invention.

Fig. 2 is a sectional side elevation of a portion of the same, showing automobiles loaded therein.

Fig. 3 is a detailed transverse section, enlarged, showing one of the hinged supports for the upper floor members.

Fig. 4 is a detailed sectional plan view taken on the line 4—4 of Fig. 3, and viewed in the direction of the arrows.

Fig. 5 is a transverse sectional detail, enlarged, of one of the clamp members for securing the wheels of the automobile to the car floor.

Fig. 6 is a detailed side elevation of the same.

Fig. 7 is a detailed elevation, enlarged, of one of the chocks for blocking the automobile wheels.

Fig. 8 is a part-sectional end elevation of the same, taken in the direction of the arrows on the line 8—8 of Fig. 7.

Fig. 9 is an interior elevation of a portion of the side of the car, showing one method of carrying the automobile wheels when removed from the automobile.

Fig. 10 is a transverse diagrammatic detail showing the means for supporting the automobile axle after the wheels have been removed therefrom.

Fig. 11 is an elevation, enlarged, of one of the lifting jacks shown in Fig. 10.

In the drawings, the reference numeral 1 represents the body of a freight car comprising a floor 2, side walls 3 and a roof 4. For the purposes of illustration, the usual

rail running wheels are indicated at 5. It is understood that the car is of the well known end-door type.

The floor 2 of the car is constructed with 5 lineally disposed grooves or channels 6, Figs. 1 and 2 of the drawings, spaced properly to receive the wheels of an automobile, and provided with hinged cover members 7 adapted to cover said channels to form a 10 level floor when the car is to be used for ordinary freight purposes. Within the channels 6 are secured runways 8, preferably formed of steel beams of channel section, as shown in Figs. 1 and 5 of the drawings, 15 and provided with laterally projecting lips 9 at the upper edges thereof.

In loading an automobile or other vehicle within our car, said automobile, shown diagrammatically at 10 in Fig. 2 of the 20 drawings, is run into the car, its wheels 11 lying within the channel members 8, as shown in Figs. 2, 5 and 7 of the drawings. The wheels 11 are then blocked to prevent lineal movement of the automobile by means 25 of the device shown in Figs. 2 and 7 of the drawings, said device comprising a chock member 12 having feet 13 adapted to rest within the channel member 8, a clamp member 14 having hooks, one of which is shown 30 at 15, for engaging the lips 9 of said channel member 8, and having also a clamp screw 16, the function of said clamp member being to hold the chock 12 securely to the channel member 8. Said chock 12 is 35 provided with an adjustable shoe 17 adapted to engage and bear against the tire 11 of the automobile wheel, said shoe having a pivotal connection 18 at its upper end with the chock 12, and being adjustably secured 40 to said chock by a clamp bolt 19, the adjustment of said shoe being provided for the purpose of enabling it to be adapted to wheels of different sizes. As shown in Fig. 2, said chock members are preferably placed 45 on both sides of each wheel of the vehicle.

A clamp member 20, Figs. 5 and 6, is provided for firmly clamping the vehicle wheel to the channel member 8. Said clamp member comprises a rigid portion 21 having at 50 one end a fixed hook 22 adapted to engage the lip 9 of the channel member 8, and at its other end an adjustable hook 23, said adjustable hook being secured to the rigid central portion 21 preferably by means of 55 a turn-buckle 24. Said clamp member is also provided with a flexible strap 25, having one end fastened to the rigid central portion 21 of the clamp at 26 and having its other end passed through a suitable buckle or clamp indicated at 27. Said strap is adapted to bear against the rim 28 of the vehicle wheel. In the application of the clamp, the rigid member 21 is placed between two adjacent spokes of the vehicle 60 wheel, and its ends 22 and 23 are hooked

over the lips 9 of the channel member 8. The strap 25 is then drawn tight upon the wheel rim 28 and the entire clamp is finally tightened by means of the turn-buckle 24.

It is understood that the channel member 70 8 extends the entire length of the car floor 2, so that as many vehicles may be placed therein as the space will permit. The chocks 12 and the clamp 20, being removable, can be secured to said channel members 8 at any 75 point in the length thereof.

We further provide in our car means for carrying a second tier of vehicles above the first tier resting upon the car floor 2. For this purpose, we provide a second floor 29, 80 Figs. 1, 2 and 3 of the drawings, said floor being divided into two equal sections lineally and preferably into two or more sections transversely, as shown in Fig. 2. Each section of said upper floor 29 is supported by 85 means of a pair of brackets, one of which is shown at 30 in Fig. 3. Said bracket is hinged at 31 to a fixed bracket 32 extending from and secured to a vertical stanchion 33, preferably forming a part of the car side 3. A brace 34 pivotally connected to the hinged bracket 30 at 35, carries at its lower end a 90 foot 36 adapted to slide vertically upon the stanchion 33, the latter, as shown in Fig. 4, being preferably composed of two spaced 95 channel section members 33'. Latch members 37 are mounted upon the stanchion 33 and are adapted for lateral sliding movement within suitable guides, not shown in the drawings, so that when moved inwardly 100 they provide bearings for the foot 36 of the brace 34, thereby holding the hinged bracket 30 in its upper or horizontal position. Said latch members 37 are preferably actuated by means of a common rod or shaft 38 extending 105 the entire length of the upper floor section 29, said rod carrying gear pinions 39 adapted to engage gear teeth 40 upon said latch members 37, so that by the rotation of said rod 38 all of the latch members 37 for 110 securing one upper floor section 29 may be operated simultaneously. To partially balance the weight of the floor section 29, counter-weights 41 are provided at the inner 115 ends of the hinged bracket 30 and tension springs 42 are also provided to assist said counterweights 41. A latch or bolt 43 is provided for securing the adjacent ends of opposite aligned swinging brackets 30 together.

The upper floor 29 is provided with channel members 8', Figs. 1 and 3, similar to the channel members 8 in the lower floor 2. Hinged covers 44 are also provided in said upper floor 29 to cover said channel members 8' to provide an unbroken floor for the 125 carrying of freight other than vehicles.

In the loading of the car, the upper floor members 29 are lowered into the position shown in full lines in Fig. 1. A vehicle is then run into the car on the lower floor 2 130

and is hoisted to the upper portion of the car, preferably by means of a suitable hoisting apparatus, indicated at 45 and carried by a rail or track 46 secured centrally of the car roof 4. The upper floor members 29 are then raised to the position shown in dotted lines in Fig. 1 of the drawings, and locked by means of the latch members 37 and the bolts 43. The vehicle is then lowered to permit its wheels to rest in the channel members 8 and is blocked and clamped in this position by means of the chocks 12 and clamps 20, hereinbefore described. If the vehicles 10 are longer than the upper floor sections 29, as shown in Fig. 2, it is understood that two or more vehicles can be raised by the means described before raising the upper floor members 29 to position. After the upper portion of the car has been loaded, another series of vehicles is run into the lower portion beneath the upper floor 29 and is secured in the channel members 8 by the described means.

It may be necessary in some cases to remove the wheels from the vehicles loaded within the car. In such case, the vehicle is run into the car, in the manner described above, and is then raised by means of suitable lifting jacks indicated at 47, in Figs. 10 and 11 of the drawings, said jacks being placed preferably under the vehicle axle 48. The wheels are then removed from said vehicle and the chocks 12 are placed in the channel members 8 under the ends of said axle 48. Said chock members 12, as shown in Figs. 7 and 8, are provided in their upper portions with adjustable clamp sockets adapted to receive and secure the ends of the vehicle axle. Said clamp sockets comprise a lower jaw member 49 having a substantially spherical seat 50 in the frame of the chock 12 and having an inclined upper surface 51 and a similar upper jaw member 52 secured by a screw 53 so that said upper jaw member 52 may be brought down upon the end of the vehicle axle to firmly clamp the same between said upper and lower jaw members.

For carrying the wheels 11 of the vehicle when removed therefrom, we provide spindles, shown at 54 in Fig. 9, each of said spindles being pivotally mounted in a bracket 55 secured to the side 3 of the car. When not in use said spindle 54 may be swung into a position parallel with the car side, in which position it projects very little from said side. Said spindle may be moved into a position at right angles to the car side, in which position the wheel 11 is placed upon said spindle and securely clamped thereon by means of a nut 56.

It will be readily seen that the car may be used for freight other than vehicles, either as a single or a double deck car. Moreover, it is to be understood that the car, although

heretofore described as particularly adaptable for the transportation of automobiles may, nevertheless, be used for the transportation of other vehicles. We, therefore, do not wish to be construed as restricting ourselves to the preferred form of our invention as hereinbefore described and with illustrations, for the reason that changes may be made in the form and construction of the invention without in any way departing from the spirit thereof, and it is therefore our desire to be understood as claiming the invention as broadly as the state of the art will permit.

Having thus described our invention, what we claim as new and desire to protect by Letters Patent is:

1. In a freight car having a floor, lineally disposed parallel channel members carried thereby and adapted to receive the wheels of a vehicle, and means associated with said channel members for securing said vehicle wheels therewithin.

2. In a freight car, a floor having lineally disposed parallel channels formed therein and adapted to receive the wheels of a vehicle, and means associated with said floor and positioned within said channels for securing said vehicle wheels to prevent movement thereof.

3. In a freight car, a floor having lineally disposed parallel channels formed therein and adapted to receive the wheels of a vehicle, and means for covering said channels to provide an unbroken floor when said channels are not used for the reception of vehicle wheels.

4. In a freight car, a floor having lineally disposed parallel channels formed therein and adapted to receive the wheels of a vehicle, and hinged cover members for covering said channels to provide an unbroken floor when said channels are not used for the reception of vehicle wheels.

5. In a freight car, a floor having lineally disposed parallel channels formed therein and adapted to receive the wheels of a vehicle, means for securing said vehicle wheels within said channels, and means for covering said channels to provide an unbroken floor when said channels are not used for the reception of vehicle wheels.

6. In a freight car having a floor, said floor having lineally disposed parallel channels formed therein and adapted to receive the wheels of a vehicle, chocks adapted to block said vehicle wheels against rotation within said channels, and means for adjustably securing said chocks within said channels.

7. In a freight car, a floor having lineally disposed parallel channels formed therein and adapted to receive the wheels of a vehicle, adjustable chocks adapted to block said wheels to prevent rotation thereof within

- 4
said channels, and means for adjustably securing said chocks within said channels.
5. In a freight car, a floor having lineally disposed parallel channels formed therein and adapted to receive the wheels of a vehicle, chocks adapted to block said wheels against rotation within said channels, and clamping devices carried by said chocks for securing the same within said channels. 70
10. 9. In a freight car, a floor having lineally disposed parallel channels formed therein and adapted to receive the wheels of a vehicle, chocks adapted to block said wheels to prevent rotation thereof within said channels, means for securing said chocks, and devices for clamping said wheels within said channels. 75
15. 10. In a freight car, a floor having lineally disposed parallel channels formed therein and adapted to receive the wheels of a vehicle, clamping devices associated with said channels and adapted to bear against the rims of said wheels to clamp said wheels within said channels. 80
20. 11. In a freight car having a floor, lineally disposed parallel channel members carried by said floor, said channel members having outwardly turned lips at the upper edges thereof and being adapted to receive the wheels of a vehicle, and clamping devices adapted to engage said lips and the rims of said vehicle wheels to clamp said wheels within said channel members. 85
25. 12. In a freight car having a floor, lineally disposed parallel channel members carried thereby and adapted to receive the wheels of a vehicle, said channel members having outwardly turned lips formed at the upper edges thereof, clamping devices for securing said vehicle wheels within said channel members, said clamping devices comprising rigid members adapted to engage the lips of said channels, and flexible members adapted to engage the rims of said 90 wheels. 95
30. 13. In a freight car, a floor having lineally disposed parallel channels formed therein and adapted to receive the wheels of a vehicle, and a second floor positioned above the first floor, said second floor having similar lineally disposed channels adapted to receive the wheels of a vehicle. 100
35. 14. In a freight car, a floor having lineally disposed parallel channels formed therein and adapted to receive the wheels of a vehicle, a second floor positioned above the first floor, said second floor having similar lineally disposed channels adapted to receive the wheels of a vehicle, and means for covering said channels to provide an unbroken floor when said channels are not used for the reception of vehicle wheels. 105
40. 15. In a freight car having side walls and a floor, said floor having lineally disposed parallel channels formed therein and adapted to receive the wheels of a vehicle, a second floor positioned above said first floor, said second floor being formed in two lineal sections, a pivotal connection between each of said sections and the car wall adjacent thereto, and means for supporting said sections in a horizontal position. 110
45. 16. In a freight car having side walls and a floor, a second floor positioned above said first floor, said second floor being formed in two lineal sections, a pivotal connection between each of said sections and the car wall adjacent thereto, and means for supporting said sections in a horizontal position. 115
50. 17. In a freight car having side walls and a floor, a second floor positioned above the first floor, said second floor being divided lineally into two sections, a pivotal connection between each section and the car wall adjacent thereto whereby said sections may assume either a horizontal position or a vertical position parallel with and adjacent to said car wall, means for supporting said sections in said horizontal position, and means for partially counter-balancing the weight of said sections when not held by said supporting means. 120
55. 18. In a freight car having side walls and a floor, said floor having lineally disposed parallel channels formed therein and adapted to receive the wheels of a vehicle, a second floor positioned above the first floor and divided lineally into two sections, a pivotal connection between each of said sections and the car wall adjacent thereto means for supporting said sections in a horizontal position, and lineally disposed parallel channel members carried by said second floor and adapted to receive the wheels of a vehicle. 125
60. 19. In a freight car having side walls and a floor said floor having lineally disposed parallel channels formed therein and adapted to receive the wheels of a vehicle, a second floor positioned above said first floor, said second floor having lineally disposed parallel channels formed therein and adapted to receive the wheels of a vehicle, a pivotal connection between said second floor and a wall of the car, means for supporting said second floor in a horizontal position, and means for elevating a vehicle within the car to enable the same to rest upon said second floor. 130
65. 20. In a freight car having side walls, a roof, and a floor, a second floor positioned above the first floor and divided lineally into two sections, a pivotal connection between each of said sections and the car wall adjacent thereto, whereby said second floor sections may be moved from a horizontal position to a vertical position parallel with and adjacent to the walls of said car, means associated with the roof of the car for elevat- 135

ing the object therein to enable the sections of said second floor to be raised to a horizontal position, and means for supporting said floor sections in said horizontal 5 position.

21. In a freight car, a floor having lineally disposed channels formed therein and adapted to receive the wheels of a vehicle, and devices positioned within said 10 channels and adapted to secure said vehicle to prevent movement thereof.

22. In a freight car, a floor having lineally disposed channels formed therein and

adapted to receive the wheels of a vehicle, and devices adjustably mounted within said 15 channels and adapted to secure said vehicle to prevent movement thereof.

In testimony whereof we have signed our names to this specification in the presence of two subscribing witnesses.
